UNITED STATES PATENT OFFICE

2,237,994

REELING DEVICE

Frederick F. Long, Chester, Pa., assignor to American Viscose Corporation, Marcus Hook, Pa., a corporation of Delaware

Application November 24, 1937, Serial No. 176,323

9 Claims. (Cl. 242—77)

This invention relates to reeling devices or swifts for reeling yarns and more particularly to such devices for use in reeling rayon threads in a wet condition, as from the cake in which the thread is deposited when formed and it is an object of this invention to provide a device of the class described which will permit of the reeling of such threads in a wet condition with a minimum of stretching of the thread and abrasion or other damage thereto both during the winding and the removal of the skein from the reel. It is also an object of this invention to provide a device of the class described which will compensate for the shrinkage during reeling of wet rayon threads, and it is a further object of this invention to provide a reeling device or swift having the arms thereof so constructed as to yield under increase of the thread tension because of shrinking of the thread and without chafing or abrading the thread.

In the drawing in which preferred embodiments of this invention are shown,

Fig. 1 is a view in elevation of a reeling device or swift constructed in accordance with this invention and shown with a plurality of skeins partly wound thereon, the skeins being broken away to show some of the swift arms more clearly;

Fig. 2 is a view in vertical transverse section of one of the swift arms, the section being taken adjacent the outer or free end of the arm;

Fig. 3 is a view in vertical longitudinal section of the yielding portion of a swift arm shown detached from its supporting means;

Fig. 4 is a view in elevation of a swift arm shown detached from the swift;

Fig. 5 is a view in end elevation of the reeling device or swift looking from the right in Fig. 1;

Fig. 6 is a vertical transverse section of a swift arm having a yielding portion of modified construction; and

Fig. 7 is a vertical longitudinal section of the yielding portion of the swift arm of Fig. 6, the section being taken as on line 7—7 of Fig. 6.

In the drawing in which there are shown only such parts of a swift as are necessary to illustrate the invention, the invention is shown in connection with a collapsible swift having the radially extending arms 1 which are pivotally secured, as at 2, to a hub 4, rotatably mounted on an axle supported by the frame 7 and driven by gears 8. Links 10 pivotally connected at their outer ends to the arms 1, as at 12, and at their inner ends to a sleeve slidably mounted on the reduced extension 6 of the hub 4 are operated by the movement of the sleeve on the extension 6 to shift the arms 1 between the position in which the yarn is wound thereon and the position in which the skein is removed from the swift.

When a swift or reeling device is in operation

60

its rotation causes a current of air to pass radially outwardly from the swift hub. Rayon thread when being wound from the cake in which it is gathered when formed is in a wet or moist condition and the passage of the air through the swift causes the thread to dry, the portion of the thread first wound being completely dried by the time the winding of the skein is finished. As the rayon thread shrinks in drying, the tension on the portion of thread first wound would greatly increase, causing the thread to stretch and rub on the swift arms, greatly weakening or rupturing the thread, unless means were provided to vary the effective diameter of the swift on which the thread is wound to compensate for the shrinkage of the thread in drying.

To compensate for the shrinkage of the thread during winding the upper members 14 of the arms 1 are formed with their upper portions of less thickness than their lower portions so as to provide shoulders or seats 16 on opposite sides of the members 14 and extending for the full length of the members 14. The seats 16 and the side faces of the upper portions of the members 14 serve as supports for members 18 of soft resilient rubber or other suitable resilient yielding material. The members 18 are shaped to form side portions 18a adapted to engage the seats 16 on the members 14 and are connected throughout their length by a curved top portion 18b of less thickness than the side portions 18a. At their ends the side portions 18a are joined by end portions 18c and 18d which, together with the side portions 18a serve to secure the members 18 in position on the arms 1. The inner end portions 18d project above the curved connecting portions 18b to form shoulders which retain the windings on the members 18 while the outer end portions 18c are finished flush with the outer surface of the curved connecting portion 18b to permit of readily removing the windings from the swift. As shown in Fig. 2, the curved connecting portion 18b is of such length that when a member 18 is applied to the member 14 of an arm, the portion 18b is spaced from the member 14 and forms a substantially cylindrical yieldable top portion for the member 14.

In use, as the thread shrinks during the winding of the skein, its tension increases, causing the curved portions 18b to be deformed, the extent of the deformation of the members 18 increasing with the increase in tension thus shortening the length of the thread necessary for the individual turns of the winding and keeping the tension on the thread to an amount which does not appreciably stretch or damage the thread as it dries. The thread commences to shrink immediately it is wound on the swift and where, with the non-yielding swift arms of the prior constructions the shrinkage was resisted and the

tension on the thread increased, with the soft resilient rubber members 18 in accordance with this invention, the shrinkage of the first strands of the thread causes a deformation or collapse of the top portion 18b, which, owing to the resilient character of the members 18, is gradual and the thread shrinks without injury or excessive strain. The gradual collapse of the member 18 decreases the effective circumference around which the succeeding strands are wrapped so that the length of the outer strands of the skein are more nearly the length of the inner strands or those first wound and the thread has not been subjected to an undesirable tension. It is also to be noted that the resilient character of the members 18 causes the strands of the skein to retain the positions in which they are placed on the swift by the traverse to a much greater degree than in prior constructions so that lacing is more readily performed and the skeins are better held by the lacings during subsequent processing, greatly reducing the production of damaged or defective thread.

In the modified construction shown in Figs. 6 and 7, the upper portion of the member 14 of the bracket 1 is reduced in thickness throughout its length to form a seat for a member 20 of soft resilient rubber. The member 20 has side portions 20a joined by end portions 20c and 20d, and a top portion 20e joining the end and side portions and forming with the end and side portions a snugly fitting cover for the reduced upper portion of the member 14 of the bracket 1. The outer end portion 20c ends flush with the top portion 20e while the inner end portion 20d projects above the top portion 20e. Secured to one side of the top portion 20e throughout the length thereof so as to form substantially an upwardly projecting extension of one of the side portions 20a is a lip portion 20f, the upper end of which projects over the top portion 20e and is spaced therefrom substantially uniformly throughout its length. At its inner end the lip portion is shaped to maintain the spacing from the shoulder formed by the inner end portion 20d so that the lip portion 20f forms a shoulder at its inner end. The lip portion 20f tapers in thickness from its junction with the top portion 20e, being of slightly less thickness at its free edge and forms a resilient yielding support for the rayon thread, which yields under the increase in the tension of the thread as the thread dries and shrinks in the same manner as does the modification of Figs. 2 and 3.

What is claimed is:

1. In a swift, an arm comprising a member having spaced longitudinally extending shoulders and forming a support and a soft rubber thread engaging member carried by said support, said rubber member comprising side portions frictionally engaging said support and carried by said shoulders and a portion supported by said rubber member and spaced from said support to yield under tension of the thread wound on the swift.

2. In a swift, an arm comprising a member having spaced longitudinally extending shoulders and forming a support and a rubber thread engaging member carried by said support, said rubber member comprising side portions frictionally engaging said support and resting upon said shoulders and a yieldable top portion arched over said support, said top portion yielding to compensate for shrinkage of thread wound on the swift.

3. In a swift, an arm comprising a support and a thread engaging member carried by said support, said thread engaging member comprising a support engaging portion and an arcuate thread engaging portion of resilient yieldable material, said thread engaging portion being secured at one side of said support engaging portion and having a free edge spaced from said support engaging portion to yield under the tension of thread wound upon the swift.

4. In a swift, an arm comprising a member having spaced longitudinally extending shoulders and forming a support and a soft rubber thread engaging member carried by said support, said rubber member being slotted to receive said support and seat on said shoulders and comprising a portion supported by said rubber member and spaced from said support to yield under tension of thread wound on the swift.

5. In a swift, an arm comprising a member having spaced longitudinally extending shoulders and forming a support and a soft rubber thread engaging member carried by said support, said rubber member comprising side and end portions forming a recess receiving said support with said side portions engaging said shoulders and a portion supported by said rubber member and spaced from said support to yield under tension of thread wound on the swift.

6. In a swift, an arm comprising a member having spaced longitudinally extending shoulders and forming a support and a soft rubber thread engaging member carried by said support, said rubber member being recessed to receive said support and seat on said shoulders for frictionally securing said rubber member to said support and comprising a portion supported by said rubber member and spaced from said support to yield under tension of thread wound on the swift.

7. In a swift, an arm comprising a support and a thread engaging member carried by said support, said thread engaging member comprising a support engaging portion recessed to receive said support and an arcuate thread engaging portion of resilient yieldable material, said thread engaging portion being secured at one side of said support engaging portion and having a free edge spaced from said support engaging portion to yield under the tension of thread wound upon the swift.

8. In a swift, an arm comprising a support and a thread engaging member carried by said support, said thread engaging member comprising a support engaging portion having spaced side members frictionally securing said member in position and an arcuate thread engaging portion of resilient yieldable material, said thread engaging portion being secured at one side of said support engaging portion and having a free edge spaced from said support engaging portion to yield under the tension of thread wound upon the swift.

9. In a swift, an arm comprising a support and a thread engaging member carried by said support, said thread engaging member comprising a support engaging portion secured thereon by its own elasticity and an arcuate thread engaging portion of resilient yieldable material, said thread engaging portion being secured at one side of said support engaging portion and having a free edge spaced from said support engaging portion to yield under the tension of thread wound upon the swift.
